CONTROL DEVICE

Harold A. Mantz, Milwaukee, Wis., assignor to
Milwaukee Gas Specialty Company, Milwaukee, Wis., a corporation of Wisconsin

Original application August 31, 1931, Serial No.
560,412. Divided and this application September 24, 1932, Serial No. 634,708

6 Claims. (Cl. 158—117.1)

This invention relates to fluid flow control systems and more particularly to a control system wherein the fluid flow is controlled from a point remote from the control device, and the control device is provided with automatically operated means for shutting off the flow of fluid.

The present application is a division of my copending application, Serial No. 560,412, filed August 31, 1931, and is directed particularly to the thermally operated shut-off for the fluid flow control means.

In the preferred embodiment of the invention, I provide a valve adapted to control the flow of fuel to a burner or similar appliance, the quantity of fuel passing through the valve being controlled from a point remote from the valve in accordance with any predetermined temperature which it is desired to maintain in the enclosure or enclosures to which the burner supplies heat. It is to be understood that any desired type of burner, remote control device, and enclosure may be combined in this system.

The valve used for controlling the flow of fuel to the burner is described in detail in my above mentioned copending application, and includes a reciprocating recessed valve stem adapted to be raised and lowered by a pivoted lever connected to the remote control means. A second pivotally mounted latch lever holds the valve stem in any desired position. A thermally actuated latch bolt is adapted to release the latch lever to permit the valve to close under spring pressure.

The latch bolt is connected, at its upper end, to a thermally sensitive member responsive to the temperature of a pilot flame, and the extinguishment of the pilot flame results in the automatic closing of the valve. Further, unless the pilot flame is ignited, the fluid flow control valve cannot be opened, due to locking engagement of the latch lever in the valve stem, which engagement is not released until the pilot flame has caused the thermally sensitive member to move the latch bolt out of locking position.

An object of the present invention is, therefore, the provision of thermally controlled means for cutting off the flow of fuel when the pilot flame is unignited, and for maintaining the control valve closed until the pilot flame is ignited.

Another object of the present invention is to provide a thermally controlled shut-off mounted directly on the valve bonnet and including a pilot flame means receiving its fuel supply from the inlet chamber of the valve directly through the valve bonnet.

A further feature of the invention is the supporting of the pilot flame head directly upon the valve bonnet, and providing for actuation of the valve closing means through the pilot head.

Other objects and advantages of the invention will appear more fully from the following detailed description, which, taken in connection with the accompanying drawing, will enable those skilled in the art to understand the construction and operation of a preferred form of the invention.

In the drawing:

Figure 1 is a vertical sectional view of the control mechanism for controlling the flow of fuel to a burner or the like;

Figure 2 is a view in side elevation of the control device for regulating and controlling the control mechanism shown in Figure 1;

Figure 3 is a front view of the control device shown in Figure 2;

Figure 4 is a detail view of the valve stem in raised position; and

Figure 5 is a detail view of the valve stem during its closing movement, showing the disengagement of the latching means.

The present invention deals particularly with a control system adapted to control the flow of fluid fuels, such as gas, to a burner, and with means for igniting the fuel issuing from the burner, by means of a control device situated at a distance from the control means.

Referring now in more detail to the drawing, in Figure 1, I have shown a valve having the valve body 5, which valve body is provided with an inlet chamber 6 and an outlet chamber 7. Suitable conduits 8 and 9 may be threaded into the inlet chamber and outlet chamber respectively, the conduit 8 leading from a suitable source of fuel supply, and the conduit 9 leading to a gas burner or the like.

Mounted upon the valve body 5 is a valve bonnet, indicated generally at 10, which is suitably secured to the valve body by means of cap screws 11, there being a gasket 12 interposed between the valve bonnet and the valve body.

The valve body 5 is provided with a threaded valve plug or seat 14, which is disposed in an opening formed in a partition wall 15 extending between the inlet chamber 6 and the outlet chamber 7, and forming a valve seat for receiving the valve member indicated generally at 18. This valve member 18 may be of any suitable construction, and preferably comprises a metal cup-shaped retaining member 19 having a leather, hard rubber, or other suitable valve seating mem-

ber 20 confined therein, the ring 19 and valve member 20 being secured to a valve stem 21 by means of the bolt 22.

The valve bonnet 10 is provided with a recessed portion 23, which is adapted to receive the packing material 24, and the washer 25, there being a spring 26 interposed between the retaining member 19 and the washer 25 for urging the valve stem 21 downwardly to close the valve. The valve bonnet 10 is also provided with a vertically extending channel 28, which, at its upper end, receives the threaded nipple member 29, this nipple member providing for a continuation of the channel and terminating at its upper end in a plug member 30 adapted to form, in conjunction with the tip 31, a tip or jet opening into the chamber 32 formed in the pilot head housing indicated generally at 33. A key 34 is adapted to hold the plug 30 in position with respect to the pilot head 33, and a continuous fuel passage from the inlet chamber 6 through the channel 28 and nipple 29 to the jet 31 is thus provided.

Disposed concentrically above the jet 31, and opening into the chamber 32, is a Venturi bushing 35, which provides for admixture of air entering the chamber 32 and fluid fuel issuing from the jet 31 to form a combustible mixture within the laterally extending channel 36 leading to the pilot flame port openings 37. A suitable hood 38 is secured about the pilot flame ports 37, by means of the screw 39, to provide for protection of the pilot flame, indicated at 40, against drafts and air currents.

The hood 38 is provided with a slotted portion 41, through which a portion of the pilot flame 40 is adapted to extend. Secured to the upper portion of the pilot flame head 33 is the thermal sensitive member 43, which comprises the two metallic strips 43a and 43b, which are suitably soldered or otherwise secured together, the strips having different coefficients of expansion. The strip 43b preferably has a greater coefficient of expansion than the strip 43a.

The thermally sensitive member 43 is secured to the pilot flame head by means of the bolt 44, and extends forwardly to a position adjacent the slot 41 formed in the hood 38, and is then doubled back and its extending end is connected, by means of rivets 45, to an extension strip 46, which strip 46 receives a threaded stud 47 at its opposite end, there being a lock nut 48 provided for adjustably positioning the stud 47 in fixed position with respect to the strip 46.

The stud 47 abuts the upper end of a motion transmitting rod 49, which extends downwardly through the chamber 32 and into a recess 50 formed in the valve stem 21. The rod 49 has bearing support in a boss 51 formed in the pilot head 33, and there is a recess 52 provided for receiving the upper end of the valve stem 21.

The valve stem 21 is recessed, as pointed out, at 50, this recess extending for a substantial distance downwardly through the axial bore of the stem. The valve stem is also provided with a plurality of angular depressions or teeth 53 near its upper external surface, and with a notch 54 adjacent its lower external surface. The stem is adapted to have reciprocatory sliding movement with respect to the valve bonnet 10 and to the pilot flame head 33. The means for providing this movement of the valve stem comprises a lever 56, pivoted at 72 to a second lever 87 which is pivotally mounted at 57 to a lateral and vertically extending portion 58 of the valve bon-

net 10. The lever 87 is adapted to have a pin and slot connection with the valve stem 21, this connection being indicated diagrammatically at 59.

The control device indicated generally at 60 in Figure 2 is adapted to be connected, by means of the flexible cable 61, to the opposite end of the lever 56, and, as described in detail in my copending application, is adapted to provide for raising or lowering of the lever to raise or lower the valve stem for controlling the flow of fuel through the valve 5. A spring 62 connected between the valve bonnet 10 and offset extension 63 of the lever 56, is adapted to provide the proper tension upon the cable 61, and to return the lever 56 to lowered position when the control device 60 is rotated toward off position.

The valve bonnet 10 is also provided with an enlarged recessed portion 65, which is adapted to receive the latch lever 66, carried by the pivot 20 pin 67. At its lower end, the latch lever 66 is provided with a detent portion 68 which is adapted to be engaged in the notch 54 formed in the valve stem 21, and when in engaged position, prevents raising of the valve stem 21, thus maintaining the valve in closed position.

At its upper end, the lever 66 is provided with a cam surface 69, adapted to be engaged by a pin 70 carried by an extending end 71 of lever 56. When in the position shown in Figure 1, the pin 30 70 bears against the cam surface 69 of the lever 66, the valve being closed. Lever 66 is held in this position by spring 62, the latch lever 66 being held locked in detent 54. Upon upward movement of cable 61, lever 56 rotates about pin 72, 35 releasing lever 66, and causing pin 70 to engage in the groove in the upper edge of lever 87, making the levers 56 and 87 rigid for upward movement about pivot 57. Further upward movement of cable 61 therefore moves levers 56 and 87 as 40 a unit about pivot 57, tending to open the valve if the pilot flame is ignited, as will be hereinafter described. When the lever 56 is lowered, spring 62 causes lever 56 to pivot about pivot 72, the pin 70 moving into engagement against the cam surface 69 of latch lever 66 to allow the valve stem 21 to drop under pressure of the spring 26. The lowering of the valve stem will pull lever 87 downwardly. Downward movement of lever 87 causes lever 56 to rotate about its cable 50 end, moving link 71 in a clockwise direction to engage pin 70 upon lever 87, thereby limiting the lowering movement of the valve stem as determined by the position of cable 61. Between the cam surface 69 and the pivot 67 of the lever 55 66, a tooth or dog member 73 is provided, which is adapted to engage in the depressions or teeth 53 of the valve stem to hold the stem in raised position when it has been lifted by the levers 56 and 87. A spring member 74 is adapted to normally urge the lever 66 into this engaged position.

Disposed within the recessed portion 50 of the valve stem 21 is a latch actuating bolt 76, having the reduced portion 77 which portion 77 has 65 camming engagement with a latch bolt pin 78.

When the bolt is in the position shown in Figure 1, the pin 78 is forced outwardly to space the dog 73 from the teeth 53, and to engage the detent 68 in the notch 54, to hold the valve in 70 closed position. However, when the pilot flame 40 actuates the thermally sensitive member 43 to cause it to warp away from the pilot head 33, the strip 46 is adapted to lift the stud 47 upwardly. This releases the engagement of the rod 75

49 in the recess 50 formed at the upper end of the bolt 76, and the bolt is forced upwardly through the recess 50 by means of the spring 81 confined between the lower end of the bolt and a reduced portion 82 of the recess 50. This causes the reduced cam surface 77 of the bolt to engage the latch bolt pin 78, and the pin 78 is forced inwardly into the recess 50 of the valve stem by means of the spring 74, the detent 68 being released from the notch 54, allowing the levers 56 and 87 to pull the valve stem 21 upwardly to open the valve, as previously described. The movement of the valve stem 21 is determined by the rotation of the control device 60, and, as indicated in Figure 3, this rotation is determined by the temperature which it is desired to maintain. A suitable dial or indicia carrying member 84 is provided, having the indications 85 thereon. Rotation of the control device 60 brings the pointer 86 selectively into position with respect to the markings or indications 85, and this rotation determines the extent to which the lever 56 is rotated into locking engagement with lever 87 and pulled upwardly. The spring 74 forces the dog 73 to engage selectively the teeth 53 carried upon the valve stem, and, as the lever 56 reaches the desired position, the dog 73 prevents the valve stem 21 from moving downwardly under the pressure of the spring 26. Thus it is apparent that the latch lever 66 is adapted to hold the valve stem in any desired position.

In operation, if the pilot flame 48 is not ignited, the thermally sensitive member 43 and the rod 49 will be in the position shown in Figure 1, and the latch bolt pin 78 will thus force the detent 68 into engagement with the notch 54, thus preventing opening of the valve by rotation of the member 60. After the pilot flame has been ignited, the expansion of the thermally sensitive member raises the rod 49, thus allowing the bolt 76 to move upwardly, allowing the pin 78 to move inwardly into the recess 50, which permits the spring 74 to disengage the detent 68 from the notch 54, and to engage the dog 73 with the desired teeth 53 on the external surface of the valve stem as the valve stem is raised by the levers 56 and 87. The latch lever 66 thus holds the valve stem in any desired raised position.

If the pilot flame should be accidentally extinguished, the downward movement of the rod 49 will force the bolt downwardly, and thus force the latch bolt pin 78 outwardly to disengage the dog 73 from the teeth 53, and the valve will close under the action of spring 26, the valve stem, when reaching closed position, being held therein by the engagement of the detent 68 in the notch 54.

This operation is shown more in detail in Figures 4 and 5, Figure 4 showing the raised position of the valve stem 21, with the dog engaging the teeth 53, and with the button 78 disposed out of engagement with the lever 66, the detent 68 of the lever being spaced away from the surface of the valve stem. As the pilot flame becomes extinguished the rod 49 forces the member 76 downwardly, as shown in Figure 5, and forces the button 78 outwardly into engagement with the surface 98 of the lever 66. This releases the dog 73 from engagement with the teeth 53, and the valve stem closes under the actuation of spring 26. As the button 78 rides down the surface 98 of the lever, it engages the cammed surface 81 disposed immediately above the pivot 87. The button, upon engaging this surface, forces the upper end of the lever 66 outwardly

to a greater extent, and at the same time forces the detent 68 into the groove 54 in the valve stem 21. This results in locking of the valve in closed position. The relative proportions and spacing of the cam surfaces 90 and 91, and of the dog 73 and detent 68, are such as to provide for disengagement of both the dog 73 and detent 68 to permit closing of the valve stem under the actuation of spring 26, the button 78 engaging the cam surface 91 to engage the detent 10 in the groove 54 for locking the valve in closed position.

When the valve has been opened, and it is desired to move it toward closed position, but not to close the valve, the remote control device 60 is rotated in a counterclockwise direction, as viewed in Figure 3, thus releasing the tension on the cable 61. The spring 62 urges the lever 56 downwardly about pivot 72, which allows the pin 78 to rotate out of the groove in lever 87 and to move slightly about the cam surface 69 of the latch lever, exerting an outward pull upon the latch lever to disengage the dog 73. The valve stem then moves downwardly under the pressure of the spring 26. When the lever 56 reaches the position desired, the lever 87, because of its connection at 59 to the valve stem, will be pulled downwardly, and thus the pin 78 will move away from cam surface 69 and will move into the groove in the upper edge of lever 87 to make the levers rigid for movement about pivot 57, thus allowing the latch lever 66 to move to the right under the pressure of the spring 74 to engage the dog 73 with the valve stem to hold it in its lowered position.

Thus it is apparent that I have provided a valve in combination with a remote control device and a thermally actuated shut-off device, whereby the valve cannot be opened unless the ignition means is ignited, and whereby, upon failure of the pilot flame or ignition means, the valve will be automatically closed. Further, I have provided a valve which is adapted to be held in any desired position, and which is opened or closed by means positioned at a point remote from the valve.

I do not intend, however, to be limited to the exact details of construction shown and described in the illustrated embodiment of the invention, but only insofar as defined by the scope and spirit of the appended claims.

I claim:

1. In combination, a valve housing, a normally closed valve therein having an axially bored valve stem, a pilot burner for maintaining a pilot flame, locking means for preventing opening of said valve when said flame is unignited, and means responsive to said flame and including a bolt slideable in said valve stem and provided with connecting means extending between said bolt and said locking means for disengaging said locking means upon ignition of said flame, and means for opening said valve.

2. In combination, a valve housing, a valve therein having a reciprocal valve stem, a pilot burner supported on said housing, means engaging said valve stem for opening said valve, spring means normally tending to close said valve, means engaging said valve stem for latching said valve in open or closed position, means responsive to the heat of said pilot burner, and means actuated by said heat responsive means for releasing said latching means from engagement with said valve stem.

3. In combination, a valve housing, a valve

therein having a valve stem mounted for reciprocal movement in said housing, means for raising said stem to open said valve, spring means biasing said valve to closed position, a pilot burner supported on said housing, said valve stem having a series of depressions and a notch formed in the surface thereof, means selectively engaging in said depressions to hold said valve in selected open position and having means engageable in said notch to hold said valve in closed position, and means responsive to the heat of said pilot burner including means for effecting release of said engaging means.

4. In a device of the class described, a valve housing, a valve therein having a reciprocal valve stem, means for reciprocating the valve stem to open and close the valve, said stem having an axially recessed portion, a latch actuating bolt slideable in said recessed portion for controlling operation of said valve, a pilot burner for maintaining a pilot flame rigidly supported on said valve housing, and means responsive to the heat of said pilot flame including means for controlling movement of said latch actuating bolt.

5. In a device of the class described, a valve housing, a valve and valve stem reciprocal therein,

said stem having an axially extending bore, means for raising and lowering said stem to open and close the valve, a latch actuating bolt slideable in said bore, a connecting pin carried in the defining wall of said bore, means for latching said stem in raised or lowered position, said pin engaging said holding means, a pilot burner for maintaining a pilot flame, and means including means responsive to the heat of said flame for controlling movement of said bolt to actuate said holding means through said pin.

6. In combination, a valve housing, a valve member therein, a pilot burner for maintaining a pilot flame, means including means responsive to the heat of said flame for locking the valve member in closed position when said burner is unignited, means for opening said valve member when said flame is ignited, spring means normally tending to close said valve, and latching means for holding said valve member in open position, said latching means being disengaged from said valve member by said heat responsive means to provide for closing of said valve member by said spring means upon extinguishment of said flame.

HAROLD A. MANTZ.
